UNITED STATES PATENT OFFICE.

HARRY A. FOOTHORAP, OF HARRISBURG, PENNSYLVANIA, ASSIGNOR TO ELLIOTT-FISHER COMPANY, A CORPORATION OF DELAWARE.

LINE-SPACE-TABULATING MECHANISM.

Application filed April 30, 1923. Serial No. 635,674.

This invention relates to line space tabulating mechanism for typewriting and similar machines.

The object of the invention is to provide a series of key controlled stops for variably determining the location of lines of writing in a manner generally similar to the determination of column or other positions by what is known as letter-space tabulating mechanism.

A subordinate object is to provide for the bodily adjustment of the entire series of stops to accommodate variations of the work sheets, as for instance, variations of the line locations on printed forms.

Another subordinate object is to provide for the retention in operative position of any stop operated and to accomplish the release and restoration of said stop to its normal operative position upon the movement of another stop to its active or arresting position.

Other subordinate objects will appear as the necessity for their accomplishment develops.

In the accompanying drawings,

Figure 1 is a plan view of a portion of a flat platen typewriter equipment with line space tabulating mechanism in accordance with my invention.

Figure 2 is a side elevation thereof.

Figure 3 is a longitudinal sectional view through the tabulator.

Figure 4 is a transverse section on the line 4—4 of Fig. 1.

Figure 5 is an elevation of one end of the tabulator with the cover plate removed.

Figures 6 and 7 are detail perspective views of the stops.

Figure 8 is a detail perspective view of the stop locking blade and its mounting.

Figure 9 is a perspective view of the tabulator block.

Figure 10 is a sectional view showing the manner in which the line space frame is gibbed to the platen frame.

Figures 11 and 12 are detail perspective views of the tabulator supporting brackets.

Figure 13 is a detail perspective view of the traveling stop.

As premised, my line space tabulator is designed, more particularly, for flat platen typewriters and is therefore shown applied to the Elliott-Fisher machine of commerce. It is not original with me to equip a machine having both letter and line spacing movements with line space tabulating mechanism in addition to the usual letter space tabulating mechanism. This broad conception is shown in Patent No. 856,344 dated June 11, 1907, to H. J. Halle.

In the drawings, 1 indicates a flat platen provided, as usual, with a platen frame, the side members of which constitute rails 2 having toothed upper edges 3 which engage the pinions of a line spacing mechanism carried by the line space frame 4 which travels longitudinally of the platen 1 and supports a carriage movable transversely of the platen to letter space the writing, and is equipped with printing mechanism and the usual ancillary mechanisms of the flat platen typewriter including letter space tabulating mechanism which arrests the carriage at predetermined positions in a manner well understood in the art. It is to facilitate the tabulating or positioning of the frame 4 longitudinally of the platen and the consequent spacing of the lines of printed matter that the present mechanism has been devised.

Bolted or otherwise secured to the right hand rail 2 of the platen frame are tabulator brackets 5 and 6 apertured to receive trunnions 7 and 8 extended from the front and rear ends of a tabulator block 9. The block 9 carries a series of tabulator stops 10 equidistantly spaced longitudinally of the platen and surmounted by keys 10^x in staggered arrangement and bearing consecutive numbers or other designations leading forwardly from the rear end of the series. The whole series of stops 10 is designed to have slight adjustment as a unit longitudinally of the platen. This adjustment is desirable to accommodate variations in the work sheets, as for instance, in the location of the printed lines on a series of forms. This adjustment is effected by the rotation of a knurled head 7^b screwed upon the trunnion 7 and bearing against the bracket 5, it being understood,

of course, that the interval between the brackets 5 and 6 is sufficient to accommodate the adjustment of the block 9 to position the stops as stated. The trunnions 7 and 8 are provided with flattened portions 7^a and 8^a for engagement with locking screws 5^a and 6^a carried by the brackets 5. The stops 10 are in the form of angular plates (see Figs. 6 and 7) and are accommodated in 10 guides 9^a formed in the outer side and top of the block 9. The horizontal upper portions 10^c of the stops are normally held in elevated or inactive positions by springs 11 for which seats 9^b are formed in the block 15. The upper ends of the springs 11 preferably engage projections 10^a on the stops as shown in Fig. 4 and the upward movement of the stops under the impulse of the springs 11 is limited by projections 10^b formed at 20 the lower ends of the stops and engaging an under face 9^c of the block 9. As best shown in Fig. 9 the outer side face of the block 9 is formed with a longitudinal recess or pocket 9^d for the accommodation of a 25 stop locking blade 12 having terminal openings 12^a adjacent to its upper edge to receive pins or trunnions 12^b extending from blocks 12^c screwed to the inner wall of the recess 9^d. The stop blade 12 constitutes, in effect, a 30 pawl common to all of the stops 10 each of which has two teeth 13 and 13^a toward which the locking blade is yieldingly urged by spring pressed plungers 12^d set in plunger sockets 9^e in the block. Any appropriate 35 means for confining the stops 10 in their guides may be provided, but by preference, a cover plate 14 is suitably secured to the outer face of the block 9. In the normal or elevated positions of the stops 10, the 40 locking blade 12 engages the lower teeth of the stops, and under these conditions the lower horizontal end 15^a of a traveling stop 15 carried by the line space frame 4 (see Fig. 4) will move freely within a guideway 45 9^f formed in the inner face of the block 9 below the normally located effective portions 10^c of the stops. If, however, one of the stop keys 10^x is depressed, the effective portion 10^c of the attached stop will be depressed (see dotted lines in Fig. 4) into interfering or obstructing relation to the traveling stop 15 and will be locked in its effective position by the engagement of the locking blade 12 with the upper tooth 13 of 50 the depressed stop. If now the line space carriage is advanced it will be arrested at the proper point by the engagement of the traveling stop 15 with the operated tabulator stop. 55 Attention is now directed to the fact that if a stop is set the line space frame may be moved to bring it into engagement with the stop. The necessity for holding the stop down during this manipulation of the ma-

chine is avoided by the provision for locking the stop in its operative position. This is advantageous, but, of course, necessitates the release of the stop when it is necessary to advance the line space frame to the next position. Such release is automatically effected by the operation of the next tabulator stop. That is to say when a stop is depressed it not only moves into effective position, but automatically effects the release of a stop previously operated and locked. This interaction of the stops will be clearly understood by reference to Fig. 4. It will be seen that operating in the manner of a pawl the stop locking blade 12 normally engaging the lower tooth 13^a will be cammed back, as the stop moves downward, until it can swing into engagement with the upper tooth to lock the stop down. Obviously, when the next stop is depressed the blade 12 will be swung back in exactly the same manner, and as soon as it has moved out of engagement with the stop previously locked by it, said last named stop will obviously be retracted to normal position. In other words, the depression of any stop will cam the locking blade out of engagement with the previously operated stop so that when any stop is moved to its operative position it will automatically release any other stop and permit its retraction. 95

It is thought that from the foregoing, the construction, operation and advantages of my line space tabulating mechanism will be fully understood, but I reserve the right to effect such variations of the illustrated structure as may fall within the scope of the appended claims. 100

What I claim is:

1. In a typewriting machine, the combination with a platen and printing mechanism, relatively movable in a direction to line space a record printed on a work element carried by the platen, of means for selecting the desired line position and for arresting relative movement of the platen and printing mechanism at such selected position, said means including coacting line selecting stops normally inoperative to arrest the relative movement of the platen and printing mechanism, certain of said stops being located in progressive line positions. 105 110 115

2. In a typewriting machine, the combination with a platen and printing mechanism, relatively movable in a direction to space the lines of a printed record, of a series of normally inactive line selecting stops occupying progressive line positions and individually movable into active position to effect line selection, and means coacting with the active stop to arrest relative movement of the platen and printing mechanism with the printing point located at the selected line. 120 125

3. In a typewriting machine, the combination with a flat platen and printing mechanism, relatively movable to line space a record printed on a work element carried by the platen, and line selecting mechanism including coating stops associated with the printing mechanism and platen, respectively, certain of said stops being extended along the platen in successive line space positions and individually movable to select the line at which the printing point will be located when relative movement of the platen and printing mechanism is arrested. 65
- 5 10 15 20 25 30 35 40 45 50 55 60 65 70 75 80 85 90 95 100 105 110 115 120 125
4. In a typewriting machine, the combination with a platen and printing mechanism movable thereover in a direction to space the lines of a record printed on a work element carried by the platen, of line selecting mechanism including a series of line selecting stops spaced along one side edge of the platen and individually movable to select a line position and to arrest the movement of the printing mechanism when such line position is reached. 75
5. In a typewriting machine, the combination with a flat platen and printing mechanism, relatively movable in a direction to line space the printed record, of a series of line selecting keys associated with the platen, and a series of line selecting stops individually movable by the keys into position to arrest the relative movement of the platen and printing mechanism at a selected line. 90
- 30 35 40 45 50 55 60 65 70 75 80 85 90 95 100 105 110 115 120 125
6. In a typewriting machine, the combination with a stationary flat platen and printing mechanism movable thereover to line space the printed record, of a series of line selecting keys located outside of the printing area of the platen, and a series of line selecting stops occupying progressive line positions and individually movable, into position to arrest the printing mechanism, upon the depression of a key to select a line. 105
- 40 45 50 55 60 65 70 75 80 85 90 95 100 105 110 115 120 125
7. In a typewriting machine, the combination of a platen and printing mechanism, relatively movable to space the printed record, of a series of line selecting keys associated with the platen, stops operated by the keys to arrest the relative movement of the platen and printing mechanism at the line selected by the particular key depressed, means for retracting the selected stop, and means whereby the operation of a key to select a new line will cause the retraction of the previously operated stop. 115
- 50 55 60 65 70 75 80 85 90 95 100 105 110 115 120 125
8. In a typewriting machine, the combination with a platen and printing mechanism, relatively movable to line space the record, of a series of normally aligned stops, and a group of line selecting keys, arranged in staggered formation, and each operative to move one of the aligned stops into position to arrest the relative movement of the platen and printing mechanism at the line selected by the depression of a key. 125
- 60 65 70 75 80 85 90 95 100 105 110 115 120 125
9. In a typewriting machine, the combination with a platen and printing mechanism, relatively movable to line space the record, of a series of normally aligned stops, a group of line selecting keys arranged in staggered formation and each operative to move one of the aligned stops into position to arrest the relative movement of the platen and printing mechanism at the line selected by the depression of a key, and means whereby the depression of a key will effect the locking thereof in depressed position and the retraction of the key previously operated. 130
- 70 75 80 85 90 95 100 105 110 115 120 125
10. In a typewriting machine, the combination with a platen and printing mechanism, relatively movable to line space the printed record, of a series of line selecting stops occupying progressive line positions and disposed along one side of the platen, keys for moving said stops individually into active position to select the line and to cause the retraction of a previously operated stop, and means for adjusting the series of stops as a unit to secure the accurate line location thereof. 135
- 85 90 95 100 105 110 115 120 125
11. The combination with a stationary platen and a movable frame, of a stop movable with the frame, and a bodily adjustable normally stationary series of stops individually movable into interfering relation with the stop first named. 140
- 95 100 105 110 115 120 125
12. The combination with a platen and printing mechanism relatively movable in the direction of line spacing, of line space tabulating mechanism including a series of tabulator stops individually movable into position to arrest the relative line spacing movement of the platen and printing mechanism, and means for effecting a unitary adjustment of the series of stops to vary the line locations. 145
- 100 105 110 115 120 125
13. In a line space tabulating mechanism, the combination with a series of tabulator stops having teeth, of a stop locking blade arranged to engage a tooth of each stop and yieldingly urged to its active position, said blade being movable to an inoperative position by any one of the series of stops to release any stop previously operated. 150
- 110 115 120 125
14. In a tabulating mechanism, the combination with a series of stops yieldingly retained in normal inactive position and each having a tooth aligned with the teeth of all the other stops, and a movable locking blade arranged to hold any stop in its operated position by engagement with its tooth and movable to release said stop by the next stop moved to operative position. 155
- 120 125
15. In a line space tabulating mechanism, the combination with a series of line selecting tabulator stops movable individually to operative position, of means for effecting the

bodily adjustment of said series of stops, means for automatically locking any operated stop, and means for effecting the automatic release of said stop upon the subsequent operation of another of said line selecting stops.

16. In a line space tabulating mechanism, the combination with a block having trans-

verse stop guides and a longitudinal recess, of stops mounted in the guides and having ratchet teeth, and a stop locking blade mounted in the longitudinal recess and disposed to engage the teeth of all the stops.

In testimony whereof I hereunto affix my signature.

HARRY A. FOOTHORAP.
